United States Patent Office.

STEPHEN C. PHILBRICK, OF ROCKVILLE, CONNECTICUT.

Letters Patent No. 71,784, dated December 3, 1867.

IMPROVEMENT IN WOOL-CARDING MACHINE.

The Schedule referred to in these Letters Patent and making part of the same.

TO ALL WHOM IT MAY CONCERN:

Be it known that I, STEPHEN C. PHILBRICK, of Rockville, in the county of Tolland, and State of Connecticut, have invented a new and useful Improvement in Wool-Carding Machines; and I do hereby declare that the following is a full, clear, and exact description thereof, which will enable others skilled in the art to make and use the same, reference being had to the accompanying drawing, forming part of this specification.

The drawing represents a sectional side elevation of my improved carding-machine.

This invention relates to improvements in the construction of carding-machines, and consists in applying additional rolls, in connection with the first breaker-card, and changing the position and run of the clothing in one of the feed-rolls, whereby the machinery is rendered much more effective in its operation.

The working parts attached to a first breaker-card are constructed in the usual way, except in respect to those parts constituting my improvements.

As in the ordinary machinery, A is the burr-cylinder, B C are the feed-rolls, D is the burr-cylinder guard-roll, and E is the tumbler. In addition to these parts, common to carding-machines, I introduce another roll, F, on the upper side of the filleting or top roll C, and I change the position of the clothing on the top feed-roll C by reversing it from the ordinary way of covering, so that, as the wool passes through the feed-rolls, it shall be held by the top roll, and combed off by the burr-cylinder A; the top roll being kept clear by the additional roll F, which thus acts as a cleaner. I also add another roll, G, forward of the guard-roll D, to work between the burr-cylinder A and the tumbler E, and take up any chunks of wool that may pass the burr-cylinder, and hold them until the burr-cylinder combs them out, after which the wool passes on to the tumbler, and so onward into the first breaker-card, all thoroughly combed, which is not the case with the present arrangement of rolls attached to the first breaker-card, much of the wool passing the burr-cylinder without having the fibre separated.

Having thus described my invention, what I claim as new, and desire to secure by Letters Patent, is—

The rolls G F, in combination with the rolls herein described, attached to a first breaker-card, all constructed, arranged, and operating as set forth.

The above specification of my invention signed by me, this 12th day of August, 1867.

STEPHEN C. PHILBRICK.
